CLAIM

The ornamental design for a portable battery charger with lid, as shown and described.

DESCRIPTION

FIG. 1 is a top, front and left perspective view of a portable battery charger with lid, shown in an open configuration; FIG. 2 is a bottom, back and right perspective view of the portable battery charger with lid, shown in a closed configuration;

FIG. 3 is a top plan view thereof;

FIG. 4 is a bottom plan view thereof;

FIG. 5 is a right elevational view thereof;

FIG. 6 is a left elevational view thereof;

FIG. 7 is a back elevational view thereof; and,

FIG. 8 is a front elevational view thereof.

The broken lines in the drawings illustrate portions of the portable battery charger with lid that form no part of the claimed design.
